(57) **CLAIM**

The ornamental design for an insect trap, as shown and described.

DESCRIPTION

FIG. 1 is a perspective view of the insect trap showing my new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is an enlarged top plan view thereof;

FIG. 8 is an enlarged bottom plan view thereof; and,

FIG. 9 is an exploded perspective view of the insect trap for clarity of the disclosure.

The broken lines throughout the drawing figures depict portions of the insect trap that form no part of the claimed design.

1 Claim, 9 Drawing Sheets
